Specification for Design.

Patented Oct. 25, 1921.

Application filed June 13, 1921. Serial No. 477,321. Term of patent 7 years.

To all whom it may concern:

Be it known that I, CHARLES H. PECK, a citizen of the United States, residing at Philadelphia, in the county of Philadelphia and State of Pennsylvania, have invented a new, original, and ornamental Design for an Ignition-Tester and Spark-Gap, of which the following is a specification, reference being had to the accompanying drawing, forming part thereof.

Figure 1 is a plan view of an ignition

tester and spark gap, showing my new design.

Fig. 2, is a side view of spark plug tester, gap and terminal.

Fig. 3, is a top plan view of testing handle, spark gap and terminal.

I claim:

The ornamental design for an ignition tester and spark gap, as shown.

CHARLES H. PECK.
